UNITED STATES PATENT OFFICE.

FELIX JOHN LEATHER, OF LONDON, ENGLAND.

HOOD FOR AUTOMOBILES AND OTHER VEHICLES.

Application filed November 8, 1926, Serial No. 147,125, and in Great Britain November 16, 1925.

This invention relates to hoods for automobile and other vehicles of the kind in which cant rails are secured to the body of the vehicle, extending from the rear to the front thereof, and a plurality of hood sticks, cross-bars or bows forming a support for a flexible covering material are provided, each of said hood sticks, cross-bars or bows being arranged in engagement with the cant rails whereby they are supported when the hood is raised, and endless flexible members, preferably actuated from the driver's seat, are employed for raising and lowering the hood.

On aesthetic grounds it is desirable to arrange the cant rails directly above the sides of the body, and on similar grounds it is desirable that the hood when lowered shall be housed within the body or, at least, when lowered shall not overhang the rear panel.

Moreover, it is most desirable or even essential that the hood should be substantially free from rattle when erected.

These and other considerations give rise to a number of difficulties in the design of a hood of the character in question.

One of the objects of the present invention is to provide an improved connection between the cant rails and the hood sticks located between the hood stick forming a support for the flexible material adjacent to the rear angle of the hood and the peak or forward end thereof which shall be of value more particularly in constructions where the portions of the cant rails supporting the hood sticks in plan conform with the sweep of the body.

According to the invention the hood sticks forming the intermediate supports for the flexible material of the hood are on either side connected to a plurality of shoes engaging the cant rail by means of links which are pivotally connected with the related hood stick about a common centre and the connections between the links and the hood sticks and the links and the shoes are secured by the employment of ball-and-socket joints.

Thus, normally, each of said hood sticks will be connected on either side to two shoes, which engage the cant rail, by means of a pair of links each formed with a ball engaging a corresponding socket in a shoe and each provided with a hemispherical bearing member at the opposite end pivotally connected with the adjacent end of the other

member of the pair of links and engaged in a member furnished with a spherical socket on the hood stick.

Conveniently, the spherical sockets are each provided with a spherical-surfaced pad and resilient means adapted to press the pad against the spherical member engaged within the socket.

The pivotal connection between the members of a pair of links is conveniently secured by providing in the adjacent plane faces of their hemispherical ends hemispherical sockets in which a ball is engaged.

Where the distance between the cant rails is less at the forward portion of the body than at the rear, the shoes are preferably arranged frictionally to engage the links when the hood stick with which they are associated is drawn forward into its appropriate position and thus to prevent relative motion between the link and the shoe.

Thus, for instance, the shoes may each comprise a portion in the form, for instance, of a lug which when the links engaged therewith are displaced as the result of the shoes being drawn forward on to the portion of cant rails above the tapered part of the body the links are caused to bear against such portions of the shoes with which they are engaged sufficiently firmly to prevent relative motion between the links and their related shoes.

Conveniently the shoes are arranged to engage flanges on the cant rail and may each comprise two halves which are secured together with the aid of location pins and a stud or the like, a member being secured to the inner half, said member comprising a recess in which a spring and a spherical-surface pad adapted to form a portion of the bearing for the ball end of the supporting link are secured in any convenient way, as for instance by the provision of a screw-threaded projection upon the said half of the shoe passing through a hole in the member and engaged by a nut.

Alternatively, in accordance with the invention, the shoes may be provided with flanged rollers engaging a corresponding flanged portion of the cant rail.

The rollers may be arranged so as to pivot about, for instance, vertical or horizontal axes according to the form of the cant rail.

Preferably the cant rails each comprise a channel portion adapted to house the flexible member whereby the hood is raised and

lowered, one wall of the channel being provided with flanges adapted to be engaged by the rollers.

Conveniently also the cant rails on their outer sides are provided with channels in which the edges of hood material may be engaged or housed, these channels being if necessary provided with weep holes or other means enabling water collecting on the hood and entering the channel to be discharged therefrom.

Each of the shoes may also be provided with means adapted to engage a button or an eyelet adapted to engage a lace or like fastening means for the flexible hood material, the edge of which is preferably welted or piped, in which case a depression or channel may be provided in the cant rail within which a welted or piped edge may be housed.

To assist further in preventing chatter or rattle of the elements of the hood construction each of the shoes may be provided with an inclined surface adapted to co-operate with a correspondingly inclined surface on the cant rail.

Thus, for instance, in a channel in the cant rail located below the upper and outer flange thereof wedge members may be provided, the location of such wedge members and their inclination being such as to cause the appropriate shoe to be seized or jammed when it has been drawn forward.

The bottom face of each shoe may be inclined correspondingly with the inclination of the wedge member with which it is to co-operate and as will be understood the heights of the several wedge members or the depths of the portions of the several shoes below the flange on the cant rail will vary in order to permit the hood sticks supporting the forward portion of the hood to pass over the wedge members which are designed to co-operate with the hood sticks situated toward the rear thereof.

Alternatively, the cant rail may be provided with wedge members or portions forming inclined planes adapted to be engaged by set-screws in the shoes which when the hood is raised will be immediately above the said inclined portions. By the use of set-screws for this purpose, adapted to co-operate with such inclined planes, adjustments may be made in order that a sufficiently tight engagement between the shoes and the cant rails may be secured.

For engaging the two hemispherical ends of each pair of links a fitting comprising two members each provided with spherical bearing surfaces, adapted to be connected to the hood stick and secured together by, for instance, a screw, is provided. Preferably the spherical surface in one of the members of this fitting is formed by arranging within a recess therein a spherical-surface pad.

A further feature of the invention com-

prises the employment of hood sticks the length or span of which may be adjusted to compensate for wear or distortion.

Certain constructions in accordance with the invention are illustrated by way of example in the accompanying drawings, in which:—

Figures 1 to 9 show various methods of connecting the intermediate supports for the flexible material of the hood with the shoes and/or their related hood sticks,

Figure 1 illustrating one method of securing the pivotal connections between the links and their related hood sticks and shoes,

Figure 2 being a fragmentary view showing a detail of this construction,

Figure 3 being a sectional elevation of an alternative construction of shoe,

Figure 4 being a corresponding plan view,

Figure 5 a section on the line 5—5 of Figure 3, the arms and cant rail being omitted;

Figure 6 is a view illustrating a further alternative construction of shoe engaging a cant rail of a form differing from those indicated in the preceding figures, while

Figure 7 is a view illustrating a further construction of shoe engaging a cant rail similar in form to the cant rail illustrated in Figure 1.

Figures 8 and 9 illustrate another alternative construction of shoe.

Figure 10 illustrates a construction of hood stick the length or span of which is capable of adjustment.

Figure 11 is a general exploded view of a hood construction as applied to a vehicle.

The following description refers generally to Figures 1 to 7.

In the construction illustrated in Figures 1, 2 and 11 the hood stick proper 1 supporting the fabric 2 is provided with a fitting comprising two halves 3 and 4 connected together by a screw 5 and providing a spherical socket 6 in which the ends of a pair of links 7 are engaged. The ends of the said links are each provided with hemispherical portions 8 and 8^a and in the plane faces of these portions recesses are formed engaging a hardened steel ball 9. The socket engaging the links is furnished with a pad 10 located in the recess 11 in which a spring 12 is arranged in order to provide a resilient bearing for the ends of the links.

The other ends of the links, only one of which is shown in Figure 1, are formed substantially as spheres 13 and each of such spheres is engaged in a recess 14 in the shoe which is built up from three main elements 15, 16 and 17. The element 15 is provided with a screw-threaded pin 18 by means of which and the nut 19 the fabric is secured to the shoe. In addition, this element of the shoe is provided with an inclined under surface 20 adapted when the associated hood

stick is in its correct position to bear against the wedge block 21 on the cant rail 22 in which a channel 23 is provided for the accommodation of the flexible member employed for raising and lowering the hood. The element 16 is engaged with the element 15 by means of a screw, not shown, and with the aid of locating pins of which one is indicated by the reference 16^a. To this element is connected the element 17 by means of the pin 24 with the screwthreaded end of which the nut 24^a is engaged. These two elements provide the socket for the spherical end of the associated link and to provide a sufficiently close but flexible engagement therewith a spherical-surfaced pad 25 is associated with the spring 26 which is located in the recess 27. When the hood is in position the link is so arranged that it bears firmly on the lip 28 on the element 16.

Referring to Figures 3 to 5, 29 are flanged rollers mounted on pins 30 in the shoe 31, the channel between the flanges on the rollers engaging the flange 32 on the cant rail which is provided also with a flange 33 adapted partly to enclose the beaded edge of the covering material. By means of the screw 34 the element 35, in which is a recess accommodating a spherical-surfaced pad 36 and the spring 37, is secured to the remaining portion of the shoe, thus forming a socket for the spherical-surfaced end 38 of the link 39.

In addition, an eyelet 40 is provided on the shoe for the engagement of a cord or lace secured to the fabric or other covering material of the hood, while a grub screw 41 is provided in the shoe, the end of the screw being arranged to bear upon a block 42 having a sloping face which will operate to cause the shoe to be held firmly in position when the hood is erected.

In the construction illustrated in Figure 6 a grub screw 43 in the cant rail 44 performs the like function, the face of the element 50 with which it co-operates being formed on the element 51 of the shoe which is also provided with an eyelet 52 adapted to engage a lace connected with the hood material. The shoe in this construction, as will be seen, is provided with flanged rollers 53 which are arranged with their axes in a substantially horizontal plane.

In the construction illustrated in Figure 7 the cant rail 22 is identical in form with the cant rail illustrated in Figure 1. The shoe comprises two main portions 54 and 55, the two portions being connected by the screw 56. The shoe in this construction is provided with a plurality of grooved rollers 57 pivoted about vertical axes and with a lug 58 which forms an abutment adapted to bear upon the inclined faces of the wedge member 59.

In the construction illustrated in Figures

8 and 9 the shoes are formed of three main portions, 60 being a saddle to which grooved rollers 61 adapted to engage the flanged cant rail are pivotally connected while 62 is a member pivoted about a rod 67 to the saddle 60 and provided with a socket 68 in which with the aid of the element 64 which is secured in position by the screw 65 the spherical end of a link connected to a hood stick may be engaged. With this construction the abutment 66 in drawing forward or erecting the hood will be engaged against a wedge block on the cant rail.

Referring to Figure 10, which illustrates a hood stick, the length or span of which may be varied, 119 and 119^a indicate the end portions of the hood stick, each of which is provided with an internally screw-threaded member 120, while 121 is a turn-buckle connecting these portions together and enabling the span of the hood stick to be increased or diminished to compensate for wear or distortion or relative displacement of the cant rails.

Having now described my invention, what I claim as new and desire to secure by Letters Patent is:—

1. A hood construction for automobile and other vehicles comprising cant rails secured to the body of the vehicle, shoe members slidable along the cant rails, a plurality of hood sticks the ends of each of which are attached to a plurality of shoe members by means of links which are connected to said shoe members and said hood sticks by ball and socket joints.

2. A hood construction comprising cant rails along which a plurality of shoe members are slidable, a plurality of hood sticks supported by the shoe members and attached thereto by links having ends of spherical form which fit to sockets on the shoe members and the hood sticks and are held therein by a spherical-surfaced pad.

3. A hood construction comprising cant rails, a plurality of shoe members slidable therealong, a plurality of hood sticks each end of each of which is supported on a pair of links the lower ends of which are carried respectively by a pair of said shoes, the upper ends of the links having hemispherical bearing portions, engaging in a spherical socket associated with the related hood stick, the lower ends having spherical bearing members engaging in sockets on the related shoe member.

4. A hood construction comprising cant rails, a plurality of shoe members slidable therealong and supporting a plurality of hood sticks by means of links, said links being secured to the shoe members by ball and socket joints, a fitting at each end of the hood sticks comprising two portions forming a spherical socket, a pair of links each having a hemispherical end being lo-

cated in said socket and held therein by a resilient and spherically-surfaced pad.

5. A hood construction according to claim 4 in which the shoe members are provided with an inclined portion adapted to coact with a wedge member on the cant rails.

6. A hood construction according to claim 4 in which the shoe members comprise two portions held together by a screw and forming a spherical socket, the lower ends of said links having ball portions located in said sockets and held therein by a spherically-surfaced pad, and a spring associated with said pad.

7. A hood construction for a vehicle comprising a cant rail on each side thereof, a plurality of shoes slidably mounted on each cant rail, links supported by said shoes and connected thereto by ball and socket joints, hood sticks supported by said links, pairs of which are connected to the ends of said hood sticks by ball and socket joints, inclined portions on said shoes adapted to coact with wedge portions on said cant rails.

In testimony whereof I have signed my name to this specification.

FELIX JOHN LEATHER.
